DEVICE FOR PRODUCING FILTERS

Bodo v. Berries, Berlin-Spandau, Helmut Ruska, Berlin-Nikolassee, and Manfred von Ardenne, Berlin-Lichterfelde, Germany, assignors to "Fides Gesellschaft für die Verwaltung und Verwertung von gewerblichen Schutzrechten mit beschränkter Haftung," Berlin, Germany, a corporation of Germany

Application April 29, 1939, Serial No. 270,858
In Germany April 30, 1938

3 Claims. (Cl. 250—154)

This invention relates to means for producing filters, in particular surface filters and ultra-filters.

The high-grade filters heretofore known, including the ultra-filters employed in colloid chemistry, are depth filters; their filter pores extend not only straight through the filter material but also run and curve in other directions, and their diameters vary considerably along each pore and between the various pores. The filter 10 properties are usually not only determined by the dimensions of the pores but depend also on the psychochemical condition of the walls of the pores.

An object of the invention is to produce ideal 15 surface filters and ultra-filters, in which the pores have a predetermined size and, if desired, thin walls of uniform thickness. Another object is to obtain surface filters, the properties of which are substantially independent of the properties of 20 the material forming the walls of the pores.

According to the invention rays of charged 25 corpuscles, for instance ions or protons, heavy as compared to electrons and focussed by electro-optical lenses, are employed in producing tiny holes in a foil as to form the filters. The electrooptical lenses are preferably of the electrostatic type because of their accelerating effect on the charged corpuscular rays. However, 30 magnetic lenses may also be employed, in which case the total flux traversing a given section thereof must be relatively great owing to the small velocity of the heavy corpuscles. The irradiation unit for producing the corpuscular rays may consist of a gas discharge tube of the cold cathode ray oscilloscope type or of a canal ray tube. Above all, canal ray tubes are suitable which, due to a particular shape of the electrodes, emit a highly concentrated ion current. Thus, 35 for instance, it has been proposed to give the anode cylinder of a canal ray tube such a shape that the beam of ion rays is focussed before passing into the acceleration chamber and to have a magnetic field act on the ions in the neighborhood of the cathode in order to dissipate the secondary electrons released at the cathode. Such arrangements have a relatively high output of rapidly flying ions and therefore are especially well suited for the purpose of the present invention.

The invention will be more clearly understood from the following description of the embodiments diagrammatically shown in the drawing in which

Fig. 1 shows a longitudinal section through a

discharge device for producing filters according to the invention, and

Fig. 2 another embodiment also in a longitudinal section. The source of the ion rays employed in both embodiments consists of a canal ray tube.

In Fig. 1, 1 denotes the anode of the ion current source; 2 the cathode, 3 the cathode aperture through which the gas chamber 4 communicates with the vacuum chamber 5. The bottom 6 of the anode 1 is provided with an aperture 7 for the passage of the positive ions. 8 and 9 are electric lenses which render the ion beam convergent and also accelerate the ions. The illustration of a voltage divider 17, having several taps connected with the anode cylinder 1, the cathode 2 and the lenses 8 and 9, serves to indicate the relationship of the potentials applied to these electrodes, all of which are positive as compared with the ground potential. The ion ray impinges on the foil 11 as indicated at 10. This foil is secured to a support 12 which may be displaced by means of an adjusting device 16 after a hole has been burnt in so that the entire foil is gradually provided with a multitude of tiny holes. A vacuum vessel 13 encloses all of the above-mentioned electrodes and lenses. When in operation, the gas chamber 4 may be continuously supplied with gas, and the vessel 13 may be continuously evacuated in order to maintain the proper pressure conditions. It is preferable to employ the same focal length for both accelerating converging lenses 8 and 9. In this case the positive ions are accelerated at both lenses approximately at the same rate.

In the embodiment shown in Fig. 2 the two lenses 14 and 15 are insulated from the grounded shields 18 and 19 surrounding the beam of ion rays, the other parts being substantially the same and designated by the same numerals as shown in Fig. 1.

In the above-described devices, the focussed beam of ion rays emitted from the irradiating unit is accelerated and focussed by the electro-optical lenses so as to have a sharply constricted cross section in the plane of incidence at the foil 11. Consequently, very great energy per unit of area is developed at the foil which is effective in burning a pore of the desired cross section 45 through the foil. The pores produced in this manner extend all in the same direction straight through the foil and have all the same diameter. The adjusting device allows producing the pores in small and uniform distances from one another. The filters thus attain a high degree of 50

uniformity and can be prepared in accurate accordance with various specifications.

What is claimed is:

1. A device for producing mechanical filters by providing a foil with filter pores, comprising in a vacuum vessel irradiation means for producing a beam of charged corpuscles heavy as compared with electrons and of an intensity sufficient for perforating said foil when in operation, a support for detachably holding said foil transverse to said beam, electrooptical lens means and an adjustable energizing circuit connected with said lens means for focussing said beam to constrict said beam in the plane of incidence in accordance with the desired diameter of the filter pores to be produced, and means for moving said foil supports laterally of said beam, said latter means being adjustable externally of said vessel, for changing the relative position of said foil and said beam to produce a multitude of pores.

2. A device for producing mechanical filters by providing a foil with filter pores, comprising in a vacuum vessel a canal ray tube for producing a beam of ion rays of an intensity sufficient for perforating said foil when in normal operation, a support for detachably holding said foil transverse to said beam, electrooptical means arranged

15 between said tube and said support for focussing said beam onto said foil, and means for moving said foil supports laterally of said beam, said latter means being adjustable externally of said vessel, for changing the relative position of said foil and said beam to produce a multitude of pores.

20 3. A device for producing mechanical filters by providing a foil with filter pores, comprising in a vacuum vessel a canal ray tube for producing a beam of ion rays of an intensity sufficient for perforating said foil when in normal operation, said tube having an anode arranged and shaped so as to prefocus said beam, a support for detachably holding said foil transverse to said beam, electrooptical means arranged between said tube and said support for focussing said beam onto said foil, and means for moving said foil supports laterally of said beam, said latter means being adjustable externally of said vessel, for changing the position of said support relative to said beam to produce a multitude of pores.
